OTHER PUBLICATIONS

Image of Target brand "Reed Diffuser" ceramic container, with a Universal Product Code of "490540611147" and distributed by Target Corporation, available at least as early as Dec. 31, 2007.

Primary Examiner—Caron D. Veynar
Assistant Examiner—Garth Rademaker

(57) **CLAIM**

The ornamental design for a reed diffuser inner vase, as shown and described.

DESCRIPTION

FIG. 1 is a perspective view of a reed diffuser inner vase showing our new design;

FIG. 2 is a front elevation view thereof, the rear, left side, and right side elevation views being identical thereto;

FIG. 3 is a top plan view thereof;

FIG. 4 is a bottom plan view thereof;

FIG. 5 is a perspective view of a second embodiment of a reed diffuser inner vase;

FIG. 6 is a front elevation view thereof, the rear, left side, and right side elevation views being identical thereto;

FIG. 7 is a top plan view thereof; and,

FIG. 8 is a bottom plan view thereof.

The broken lines depict environmental subject matter only and form no part of the claimed design.
